UNITED STATES PATENT OFFICE.

SALATHIEL WISE STALNAKER, OF FLAT WOODS, WEST VIRGINIA.

FOLDING CRATE.

1,111,811.

Specification of Letters Patent. Patented Sept. 29, 1914.

Application filed July 23, 1913. Serial No. 780,836.

To all whom it may concern:

Be it known that I, SALATHIEL WISE STALNAKER, a citizen of the United States, residing at Flat Woods, in the county of 5 Braxton and State of West Virginia, have invented certain new and useful Improvements in Folding Crates, of which the following is a specification, reference being had to the accompanying drawings.

10 This invention relates to improvements in folding crates, poultry coops and the like and has for its primary object to provide a crate which may be very easily and quickly folded so that the same can be compactly 15 arranged for convenience in transportation.

The invention has for a further object the provision of an improved form of latch device to support the foldable sections of the 20 crate in their erect positions and to also retain the same in their superposed collapsed position.

The invention has for still another object to generally improve and simplify the construction of devices of this character, to increase 25 their durability and serviceability in actual use and to produce a crate or coop which can be manufactured at small cost.

With the above and other objects in view as will become apparent as the description 30 proceeds, the invention consists in certain constructions, combinations and arrangements of the parts that I shall hereinafter fully describe and claim.

For a full understanding of the invention, 35 reference is to be had to the following description and accompanying drawing, in which—

Figure 1 is a perspective view of my improved crate or coop illustrating the preferred embodiment thereof. Fig. 2 is a plan view of the crate, folded. Fig. 3 is an end elevation thereof.

Referring in detail to the drawings, 5 designates the bottom of a coop or crate 40 which is provided upon the under side thereof and at its opposite ends with the transverse cleats 6. To the longitudinal edges of this bottom, the bars or cleats 7 are secured. Upon the upper edges of these longitudinal bars, the side walls 8 of the crate 50 are hinged as indicated at 9.

10 designates the end members of the crate structure which are hinged directly to the upper surface of the bottom 5 as shown at 55 11. Each of the side and end members of the crate consists of a rectangular frame the

longitudinal bars of which are connected by means of the spaced vertical rods 12. These rods in the end members of the crate project above the upper longitudinal bars thereof as 60 indicated at 12' for a purpose which will be later referred to.

The top 13 of the crate also consists of a rectangular frame, the end bars thereof being connected by the additional longitudinally extending spaced bars 14. These bars as well as the outer side bars of the top frame are connected by a plurality of spaced rods 15 upon one of which a door 16 is loosely mounted. This door is provided 70 with a resilient catch rod 17 which is fixed at one end to said door and is adapted for engagement at its other end with one of the transverse rods 15 to hold said door in its closed position. The end bars of the top 13 are provided with spaced openings 18 which correspond in number with the number of rods 12 in the ends 10 of the crate. By providing the longitudinal bars 7 upon which the sides of the crate are mounted, it will 80 be noted that the upper longitudinal bars of said sides extend above the ends of the crate. The top 13 is adapted to be placed between the side members 8, the upwardly extending ends 12' of the rods 12 in the ends of the 85 crate being received in the openings 18. Thus the top 13 serves to hold the ends in their erect positions and the top in turn is held against longitudinal shifting movement. 90

To each end of each of the side members 8, a resilient catch member 19 is fixed at one of its ends. This member is provided with a loop or bend 20 in its other end which is adapted for engagement in a notch or recess 95 21 provided in the end of the top 13. It will thus be seen that when the crate is set up in use, all of the sections thereof are securely held against collapse. When it is desired to fold the crate, the catch members are released from engagement with the top section and said top section is removed. The ends of the crate are then folded inwardly upon the bottom thereof and the top 13 is placed upon the end sections, the longitudinal side 100 bars of said top frictionally engaging the knuckles of the hinges 9 which connect the sides 8 to the longitudinal bars 7, so that said top member cannot shift longitudinally. The side members 8 of the crate are then 105 folded inwardly upon the top 13, the loops 20 of the catch members 19 on the side mem- 110

bers engaging beneath the end bars of the top 13, and securely holding the side members in their folded positions. It will thus be seen that the several sections of the crate 5 are very compactly arranged so that a large number of crates can be conveniently transported.

From the foregoing, it is believed that the 10 construction and manner of operation of my improved folding crate or coop will be clearly and fully understood.

The device is simple and durable in its 15 construction, highly convenient and serviceable in practical use and may be manufactured at small cost.

While I have shown and described the 20 preferred construction and arrangement of the several parts, it will be obvious that the invention is susceptible of considerable modification in the form, proportion and arrangement thereof without departing from the essential features or sacrificing any of the advantages of the same.

Having thus described the invention, what 25 is claimed is:

A folding crate or coop comprising a bottom, side and end sections hingedly mounted upon said bottom, said side and end sections each consisting of a rectangular frame,

rods connecting the longitudinal bars of said 30 frame, the rods of the end sections projecting above the top bars thereof, a top section provided with openings in its opposite ends to receive the projecting rods of the end sections whereby said ends are supported in 35 their erect positions and the top held against longitudinal movement, said top section being further provided in its opposite ends and adjacent its longitudinal edges with recesses, and catch members carried by the 40 side sections to engage in said recesses and retain the parts in their erect positions, said end sections being foldable upon the bottom of the crate, and the top section adapted for arrangement upon the end sections to frictionally engage the hinges of the side sections, said side sections being foldable inwardly upon said top section and the catches of said side sections engaging the ends of the top section to retain the parts in their 50 collapsed positions.

In testimony whereof I hereunto affix my signature in the presence of two witnesses.

SALATHIEL WISE STALNAKER.
